NEEDLING MACHINE

Patrick H. Walsh, Newtonville, Mass., assignor to
Caro Cloth Corporation, Carolina, R. I., a corporation of Delaware

Application May 19, 1930. Serial No. 453,428

11 Claims. (Cl. 28—4)

My present invention is a novel and improved needling machine particularly adapted for needling textile fabrics through and incorporating the same with a base fabric, as well as with the fibres themselves.

An object of the present invention is the provision of an improved machine for forcing the fibres which constitute the bat or web through the base fabric in such a manner as to produce an even texture in the resultant article.

Another and important object of the present invention resides in the provision of a plurality of banks of needles, each bank being a continuous unbroken bank, and said plurality of banks being arranged in parallelism.

I preferably utilize two of these longitudinal banks of needles, and find that this use of two banks will result in a well balanced machine, reducing vibration to a minimum and operating in a smooth efficient manner.

These two banks of needles are alternately reciprocated, so that while one bank is descending to effect the needling operation, the other bank is ascending, the stroke of each bank balancing the stroke of the other bank.

Another object of my invention resides in the novel arrangement of the needles in each bank. Each bank has a plurality of rows of needles, the needles in each row being arranged in pairs, and each pair of needles being staggered relative to its adjacent pairs. In this manner, on each descent of a bank, a large area of the fabric will be operated upon by each bank of needles, followed in rapid sequence by the needling operation of the succeeding bank, which will result in the complete needling of the entire textile fabric being fed through the machine.

Another feature of my invention resides in the novel manner in which the needle bar holding frames are mounted, said frames being pivotally mounted to enable the same to be swung away from the fabric being operated upon, for the purpose of quickly and easily removing and replacing needles when necessary.

Means are also provided for locking the needle frames in operative position, said means being readily operable to release said frames to permit the pivotal action above referred to.

Another feature of the invention resides in the provision of novel means to effect relative adjustment between the needle banks, so that said banks may be spaced a desired distance from each other.

Another object of the invention resides in the provision of novel means to effect an orbital

movement of the needle banks during their operation. Thus, as the fabric is fed or pulled through the machine, the needles will penetrate the base fabric, forcing the fibres therethrough, and said needles will travel with said fabric during the interval of time necessary to effect the penetration of said needles through the base fabric and their withdrawal therefrom.

Other novel features and objects of the invention reside in the particular construction and arrangement of various parts of my machine.

The above, and other objects and features of the invention, will be hereinafter more fully pointed out, described and claimed.

Referring to the drawings illustrating a preferred embodiment of the present invention,

Fig. 1 is a front elevation of my novel needling machine;

Fig. 2 is an end elevation of said machine;

Fig. 3 is a vertical sectional view on the line 3—3 of Fig. 1;

Fig. 4 is a central sectional elevation of one end of said machine;

Fig. 5 is a cross sectional view on the line 5—5 of Fig. 4;

Fig. 6 is a partial plan view of said machine;

Fig. 7 is a vertical sectional view on the line 7—7 of Fig. 4;

Fig. 8 is a vertical sectional view on the line 8—8 of Fig. 4;

Fig. 9 is a vertical sectional view on the line 9—9 of Fig. 3;

Fig. 10 is a fragmentary plan view of one of the stripper elements;

Fig. 11 is a partial plan view of one of the needle banks;

Fig. 12 is an end elevation of one of the needle banks; and

Fig. 13 is an enlarged side elevation of one of the needles utilized.

Referring now to the drawings for a particular description of the invention, its construction, assembly and operation, my novel machine comprises a pair of bases 1 from which extend vertical standards 2, said standards being split at their upper ends, as illustrated at 3, said split portions being united by bolts 4 extending through the webs 5, a lever 6 being provided to tighten or loosen said webs as desired.

Slidable in each standard 2 is a post 7 having a threaded interior 8, a threaded shaft 9 being threaded into said post 7.

A beveled gear 10 is fixed to the lower end of the shaft 9, and meshing with said beveled gear 10 is a beveled gear 11 fixed on the shaft 12, said

shaft 12 being rotated by handles 13. A bearing bracket 14 is fixed to each standard 2 by means of bolts 15, this bearing bracket being provided with bearings for the shafts 9 and 12, thus insuring meshing of the gears 10 and 11 one with the other.

A collar 16 is fixed to the shaft 9, and interposed between the collar 16 and bracket 14 is a thrust bearing 17. Pivotedly mounted at the top 10 of each post 7 is a shaft 18, a bearing member 19 being clamped to the outer end of said shaft by means of a bolt 20 through the webs 21, and a collar 22 is secured to said shaft by said screw 23 to prevent longitudinal displacement of said 15 shaft.

Pinned at each end to said shafts 18 is a casting 24, said casting 24 having thereon vertically extending bearing members 25, through which extends a crank shaft 26, said crank shaft 26 20 also having a bearing at each end, in the bearing members 19.

Adjacent to each end of the crank shaft 26 is a sprocket 27, and rotation is imparted to said crank shaft by means of chains 28, said chains 25 28 being in turn driven by sprockets 29 mounted on a shaft 30, said sprockets 29 being rotated by chains 31 traveling over sprockets on a shaft 32 mounted in suitable bearings on a support 33, said shaft 32 being driven from any suitable 30 source of power.

A link 34 extends between the shafts 32 and 30, and a link 35 extends between the shafts 30 and 26, these links being freely movable on said shafts.

35 For convenience, the crank shaft 26 is provided with six throws, arranged in sets of three. As clearly shown, three of the throws of the crank shaft will be in their lowermost position when the other three throws are in their uppermost position.

A pair of frames 36 and 37 are provided, extending longitudinally of the machine. Each of these frames has fixed thereto by bolts 38 a plurality of yoked bosses 39, each of these bosses being provided with a wrist pin 40. A plurality of connecting rods 41 are rotatably mounted on the crank shaft 26, and connected to the wrist pins 40 on the frame 36, and a plurality of connecting rods 42 are rotatably mounted on the 50 crank shaft 26 and connected to the wrist pins 40 on the frame 37.

Fixed to the casting 24 by bolts 43, are a pair of blocks 44, one of the blocks being provided at each end of the casting 24. Rotatably mounted 55 in each block 44 are shafts 45 and 46, fixed to which are keys 47 and 48. The frame 36 is provided with a keyway 49, and the frame 37 is provided with a vertical recess 50 within which is mounted a shoe 51 having therein a keyway 52. The keys 47 and 48 are adapted to seat in the keyways 49 and 52 respectively.

The shafts 45 and 46 project above the casting 24, and fixed to the upper end of the shaft 45 is a bracket 53 carrying a roller 54, and fixed to the 65 shaft 46 is a bracket 55 carrying a roller 56. A member 57 is fixed to the crank shaft 26, and has therein cam slots 58 and 59 adapted to be respectively engaged by the rollers 54 and 56.

70 It will thus be apparent, that on rotation of the member 57, a rotative movement will be imparted to the shafts 45 and 46, causing the keys 47 and 48 to move the frames 36 and 37 back and forth laterally with respect to the blocks 44.

75 Simultaneously therewith the crank shaft 26 will cause the connecting rods 41 and 42 to alter-

nately depress the frames 36 and 37, so that during the reciprocation of the frames 36 and 37 they will have a slight orbital movement.

Reinforcing webs 60 are fixed to the blocks 44 by bolts 61.

Fixed to the bottom of the frame 36 is a needle bar 62 and fixed to the bottom of the frame 37 is a needle bar 63. The construction of these needle bars and their needle holding devices is identical. Each of these bars has a plurality of threaded apertures 64 therethrough, and cooperating therewith are bolts 65 to hold the bars 62 and 63 on their respective frames 36 and 37. Each needle bar is provided with a plurality of rows of needles 66, and each row of needles is composed of needles arranged in pairs, each pair of needles being staggered from the adjacent pairs of needles in its row. Set screws 67 and 68 are provided, the set screws 67 being longer than the screws 68, and the needle bars 62 and 63 are each provided with transverse threaded recesses 69, these recesses terminating adjacent to the vertical recesses through which the needles 66 are inserted.

Thus when the screws 67 and 68 are threaded 100 inwardly, they will bind the needles 66 in their vertical recesses, thus constituting a simple and efficient needle holding arrangement.

It will be noted that each needle bar 62 and 63 is a continuous unit, and extends along the 105 length of their respective frames 36 and 37. In order that the needle bars and their banks of needles may be adjusted toward or from each other, I provide, in the frame 37, an adjusting screw 70 and an adjusting screw 71. The screw 110 70 bears against the outside of the shoe 51, and on being threaded inwardly will force the shoe 51 to the opposite side of the recess 50. The adjusting screw 71 is threaded into the shoe 51, and may be operated to draw the shoe 51 to the side of the 115 recess 50 at which the screw 71 is located. This adjustment will increase or decrease the space between the banks of needles 66 within a sufficient range for all practical purposes.

From the above description it is obvious that, 120 upon rotation of the crank shaft 26, the connecting rods 41 and 42 will be alternately raised and lowered, effecting an alternate raising and lowering of the frames 36 and 37 and their respective banks of needles. The rotative action of the keys 125 47 and 48, effected by means of the cam member 47, will also produce a motion of the frames 36 and 37 and hence their respective needle banks in a substantially horizontal plane. The needle bars 62 and 63 will thus be given a movement in a 130 closed path, it being understood that the rotation of the crank shaft 26 and cam 57 is such as to give a complete oscillatory or transverse movement to the frames 36 and 37 for each complete reciprocating motion given thereto.

It will also be appreciated that the speed of travel of the fabric 72 being needled, is equal to the transverse speed of the needle bars 62 and 63. The needles 66 carried by the needle bars 62 and 63, therefore, enter the base fabric carrying 140 the fibres of the bat or web therewith, and move along with the base fabric during the penetrating and withdrawing movement, accomplishing this complete movement without drag or strain on either the needles or the fabric. The fabric 72 145 is fed through the machine by any suitable feeding device, such as indicated at 73 in Fig. 3, said feeding device moving the fabric in a plane transversely to the movement of the banks of needles 66.

A freely mounted pressure roll 74 is mounted in suitable supports 75, the bottom of said roll being slightly below the top of the bed plate 76, the roll 74 thus exerting a pressure on the fabric 5 72. The bed plate 76 has a central web 77, and transverse webs 78. Secured to the top of the webs 78 by bolts 79 are longitudinally extending webs 80. The tops of the webs 80 and webs 77 are flush with the top bed plate 76, and provide suitable spaces to permit the entrance of the needles 10 66 and the slight transverse movement given thereto, the spaces thus provided not being sufficient to permit any appreciable sag or bend in the fabric 72 during the needling operation.

15 In order to insure that the fabric will not be drawn upwardly to any material extent by the needles 66 on their return stroke, I provide stripper elements. One of these elements comprises a plate 81 carried by the brackets 82, and having 20 a shaft 83 extending throughout the length thereof on which are mounted a plurality of idler rolls 84.

At the opposite side of the machine a shaft 25 85 is carried by the arms 86 and in turn carries a roll 87 spaced approximately the same distance above the bed plate as the rolls 84. These rolls or strippers will insure against either the mat or the base fabric being raised to any material extent by the needles during their upward stroke.

30 In order to enable the needles 66 to be easily removed and replaced, in case of breakage, I provide, at each side of the blocks 44, a fixed dog 88 mounted on a plate 89, said plate being fixed to the standard or upright 2. Extending 35 longitudinally through the plate 89 is a shaft 90, and fixed to said shaft 90 is a dog 91, at the side of the block 44 opposite the dog 88. Also fixed to the shaft 90 is a lever 92 having a manipulating handle 93 thereon. The structure as thus described is duplicated at each end of the machine, and in order to simultaneously release both of the dogs 91, I provide a link or connecting rod 94, having a yoke 95 at each end thereof, and pivot pins 96 connecting said yokes to the levers 40 92.

45 Thus, on throwing the levers 92 to the left, as viewed in Fig. 1, dogs 91 will be withdrawn from operative position, permitting shafts 18 to rock in the upper ends of the posts 7, swinging the entire casting 24, blocks 44, needle frames 36 and 37, and the needle bars and needles carried thereby away from the bed plate, to the position illustrated in dotted lines in Fig. 3. The bearing members 19 will also rock with said shafts 18, carrying the crank shaft 26 therewith, the links 34 and 35 permitting the driving chains and sprockets to move with the movement of the crank shaft, without damage.

When the machine is swung to the position 50 illustrated in dotted lines in Fig. 3, any desired needle or needles 66 may be removed from their respective bars and replaced. Thereupon the machine will be swung back to normal position, the lever 92 thrown to the right to the position illustrated in Fig. 1, and the dogs 91 and 88 will effectually hold the machine in operative position until it is again desired to have access to the needle banks.

Because of the mass formation of the needles 55 70 66, said needles will produce a needling operation in which the fibres will be needled into and through the base fabric at predetermined spaces or on predetermined lines, resulting in a closely needled fabric.

75 The operation of my machine is simple, and will

be readily understood by those skilled in the art, being briefly described as follows:

Let it be assumed that my machine is constructed as above described, and that a suitable or desirable base fabric is being fed transversely 80 to the reciprocating motion of the needles 66. Also assume that on the base fabric is placed a web of fleece, or if desired a plurality of super-imposed webs of fleece, and that such base fabric with the super-imposed web or webs thereon is being moved at the proper speed. Power being imparted to the machine by means of the chains 31 and 28, the needle bars 62 and 63 will be reciprocated and oscillated in their closed path, alternately and in the manner above described. The closed path 85 of the needles 66 is illustrated in dotted lines at 97, the downward movement of the needle being on the side of the arrow 98, the fabric 72 moving in the direction of the arrow 99.

The feeding movement of the base fabric and super-imposed web or webs will be equal to the lateral or transverse movement of the needles 66 caused by the cam 57 and rollers 54 and 56. After the needles 66 in each bar 62 and 63 have reached their lowermost position, they will then 100 be withdrawn by continued rotation of the crank shaft 26 still being laterally moved in synchronism with the base fabric until the needles 66 are withdrawn clear of the webs of fleece and base fabric, the stripper elements insuring that neither the 105 webs of fleece nor base fabric will be raised from the bed plate to any appreciable extent.

It will thus be understood and appreciated by those skilled in the art that I have devised an improved needling machine containing many 110 novel features and elements, and since I believe said machine, as well as said features and elements are novel, I have, therefore, claimed same broadly in the present application.

While I have necessarily illustrated and described my present invention somewhat in detail, it will be understood that I may vary the size, shape, and arrangement of parts within reasonably wide limits without departing from the spirit of the invention.

115 My invention is further described and defined in the form of claims as follows:

1. An improved needling machine of the kind described, comprising a pair of parallel frames, a needle bar on the bottom of each frame, needles 120 carried by said bars, means to alternately reciprocate said frames, each of said frames having a vertical keyway therein at each end thereof, a block at each end of said frames, shafts in said blocks, a vertical key on each shaft adapted to 125 seat in said keyways, and means to effect a rotative movement of said shafts, whereby an orbital motion will be imparted to said frames during their reciprocation.

2. An improved needling machine of the kind described, comprising a pair of parallel frames, a needle bar on the bottom of each frame, needles carried by said bars, means to alternately reciprocate said frames, each of said frames having a vertical keyway therein at each end thereof, a 140 block at each end of said frames, shafts in said blocks, a vertical key on each shaft adapted to seat in said keyways, and means to effect a rotative movement of said shafts through a predetermined arc, whereby an orbital motion will be imparted to said frames during their reciprocation.

3. An improved needling machine of the kind described, comprising a pair of parallel frames, a needle bar on the bottom of each frame, needles carried by said bars, means to alternately recipro- 145

- cate said frames, each of said frames having a vertical keyway therein at each end thereof, a block at each end of said frames, shafts in said blocks, a vertical key on each shaft adapted to seat in said keyways, and cam operated means to effect a rotative movement of said shafts, whereby an orbital motion will be imparted to said frames during their reciprocation.
4. An improved needling machine of the kind described, comprising a pair of parallel frames, a needle bar on the bottom of each frame, needles carried by said bars, means to alternately reciprocate said frames, each of said frames having a vertical keyway therein at each end thereof, a block at each end of said frames, shafts in said blocks, a vertical key on each shaft adapted to seat in said keyways, and cam operated means to effect a rotative movement of said shafts through a predetermined arc, whereby an orbital motion will be imparted to said frames during their reciprocation.
5. An improved machine of the kind described, comprising a pair of vertically movable posts, a shaft rotatably mounted in each of said posts, a frame fixed to said shafts, a block fixed to said frame at each end thereof, vertical shafts in said blocks, a key on each shaft, a pair of parallel frames, a needle bar on the bottom of each frame, needles carried by said bars, each of said frames having a vertical keyway therein at each end thereof adapted to be engaged by said keys, bearing members fixed to the shafts in said posts, a crank shaft rotatably mounted in said bearing members, connecting rods on said crank shaft and fixed to said parallel frames, and means to rotate said crank shaft to effect alternate reciprocation of said parallel frames.
6. An improved machine of the kind described, comprising a pair of vertically movable posts, a shaft rotatably mounted in each of said posts, a frame fixed to said shafts, a block fixed to said frame at each end thereof, vertical shafts in said blocks, a key on each shaft, a pair of parallel frames, a needle bar on the bottom of each frame, needles carried by said bars, each of said frames having a vertical keyway therein at each end thereof adapted to be engaged by said keys, bearing members fixed to the shafts in said posts, a crank shaft rotatably mounted in said bearing members, connecting rods on said crank shaft and fixed to said parallel frames, and means to rotate said crank shaft to effect alternate reciprocation of said parallel frames, all parts carried by the shafts in said posts being tiltable out of operative position.
7. An improved machine of the kind described, comprising a pair of vertically movable posts, a shaft rotatably mounted in each of said posts, a frame fixed to said shafts, a block fixed to said frame at each end thereof, vertical shafts in said blocks, a key on each shaft, a pair of parallel frames, a needle bar on the bottom of each frame, needles carried by said bars, each of said frames having a vertical keyway therein at each end thereof adapted to be engaged by said keys, bearing members fixed to the shafts in said posts, a crank shaft rotatably mounted in said bearing members, connecting rods on said crank shaft and fixed to said parallel frames, means to rotate said crank shaft to effect alternate reciprocation of said parallel frames, all parts carried by the shafts in said posts being tiltable out of operative position.
8. An improved machine of the kind described, comprising a pair of vertically movable posts, a shaft rotatably mounted in each of said posts, a frame fixed to said shafts, a block fixed to said frame at each end thereof, vertical shafts in said blocks, a key on each shaft, a pair of parallel frames, a needle bar on the bottom of each frame, needles carried by said bars, each of said frames having a vertical keyway therein at each end thereof adapted to be engaged by said keys, bearing members fixed to the shafts in said posts, a crank shaft rotatably mounted in said bearing members, connecting rods on said crank shaft and fixed to said parallel frames, and means to rotate said crank shaft to effect alternate reciprocation of said parallel frames, all parts carried by the shafts in said posts being tiltable out of operative position, a member fixed to said crank shaft and having a plurality of cam paths therein, a roller associated with each of said key shafts and adapted to ride in said cam paths, whereby a partial rotative movement will be imparted to said key shafts and keys to effect an orbital movement of said parallel frames during their reciprocation.
9. An improved machine of the kind described, comprising a pair of vertically movable posts, a shaft rotatably mounted in each of said posts, a frame fixed to said shafts, a block fixed to said frame at each end thereof, vertical shafts in said blocks, a key on each shaft, a pair of parallel frames, a needle bar on the bottom of each frame, needles carried by said bars, each of said frames having a vertical keyway therein at each end thereof adapted to be engaged by said keys, bearing members fixed to the shafts in said posts, a crank shaft rotatably mounted in said bearing members, connecting rods on said crank shaft and fixed to said parallel frames, means to rotate said crank shaft to effect alternate reciprocation of said parallel frames, all parts carried by the shafts in said posts being tiltable out of operative position, a member fixed to said crank shaft and having a plurality of cam paths therein, a roller associated with each of said key shafts and adapted to ride in said cam paths, whereby a partial rotative movement will be imparted to said key shafts and keys to effect an orbital movement of said parallel frames during their reciprocation.
10. A device of the character described comprising a frame, a work table on the frame, vertical guides carried by the frame, means to pivot the guides on the frame, a head slidably mounted between the guides, means to reciprocate the head vertically between the guides, and means to reciprocate the head horizontally.
11. A device of the character described comprising a frame, a work table on the frame, vertical guides carried by the frame, a head slidably mounted between the guides, means to reciprocate the head vertically between the guides, and means to reciprocate the head horizontally.

PATRICK H. WALSH.
